UNITED STATES PATENT OFFICE.

JAMES W. BUSH, OF SCIOTOVILLE, OHIO.

PAPER-HOLDING DEVICE.

SPECIFICATION forming part of Letters Patent No. 603,316, dated May 3, 1898.

Application filed October 21, 1897. Serial No. 655,937. (No model.)

To all whom it may concern:

Be it known that I, JAMES W. BUSH, a citizen of the United States, residing at Scioto-ville, in the county of Scioto and State of Ohio, 5 have invented certain new and useful Im-
provements in Devices for Holding Tissue-Paper and Alcohol; and I do declare the fol-
lowing to be a full, clear, and exact descrip-
tion of the invention, such as will enable oth-
ers skilled in the art to which it appertains to
make and use the same.

My invention contemplates the provision of a simple and compact device for holding and permitting of the convenient use of alcohol 15 and tissue-paper in cleaning and polishing the lenses of eyeglasses.

The invention will be fully understood from the following description and claims when taken in conjunction with the annexed draw-
ings, in which—

Figure 1 is a perspective view of one em-
bodyment of my invention, which is designed
for use in the home or office. Fig. 2 is an en-
larged diametrical section of the same. Fig. 25
3 is a detail section taken in the plane indi-
cated by the line $x-x$ of Fig. 1.

Referring by letter to said drawings, A des-
ignates the casing of my improved device,
which is circular in form and is preferably
30 made of wood, although other material may
be employed when desired. This casing (see
Fig. 2) comprises an annular vertical wall a ,
a bottom wall b , and a top wall c , the latter
being fixedly connected to the upper edge of
35 the wall a and being provided with a central
aperture d for a purpose presently described.
The annular vertical wall a is rabbeted at its
lower edge, as indicated by e , and in this rab-
bet the bottom wall b is arranged and remov-
40 ably secured by the pin f , which is fixed to
the bottom wall and is designed to take into
a socket g in the vertical wall, and the spring-
pressed bolt b , which is arranged at an oppo-
site point with respect to pin f and is designed
45 to take into a socket i in the vertical wall.
By moving the bolt h inwardly toward the
center of the case one side of the bottom b is
disconnected from the wall a , after which the
other side of said bottom may be readily dis-
50 connected by withdrawing the pin f from
socket g , and the bottom may then be re-
moved for a purpose presently described.

From this the manner of replacing and secur-
ing the bottom in the wall a is obvious and
need not be described.

The bottom wall b is provided on its upper
side with two or more antifriction-rollers j ,
and it is also provided with a central pivot-
pin k , as shown. Mounted and designed to
turn on said pin k and bear on the rollers j is 60
a disk B , which has for its purpose to support
and permit of free rotation of an annular
spool C . The said spool C is preferably of
pasteboard of the form shown, and it is de-
signed to receive the tissue-paper (indicated 65
by l) and has a large central opening m , as
shown. In this opening m of the spool is ar-
ranged a frame n , which has a flange p , rest-
ing in a rabbet q of the top wall c , and also
has a flange r at its lower end. Resting on 70
this latter flange r and within the frame n is
a bottle D , which is designed to contain al-
cohol. This bottle D is retained in position
by a cap-plate s , which is flanged, as indi-
cated by t , to engage the inner side of the 75
frame n , and said bottle is closed by a stop-
per E , to which a piece of wire F is connect-
ed, the latter being designed to carry a bunch
of fibrous material G , as shown.

In order to permit of ready removal of the 80
tissue-paper from the casing A , said casing
is provided with a slot u , (see Fig. 3,) which
has a rounded lip v at one side and a pivoted
spring-pressed clamp w at the opposite side,
as shown. The tissue-paper is carried from 85
the spool C , through the slot u , between the
lip v and the clamp w , as shown in Fig. 1.
When a piece of paper is desired for the pur-
pose of cleaning a pair of glasses, the extended
end of the paper is grasped and the quantity 90
desired is drawn from the spool and casing,
after which it is cut, the outer edge of the
lip v being sharpened for this purpose. When
the piece of tissue-paper is cut in the manner
described, the end of the remainder on the 95
spool is clamped between the clamp w and
lip v , when another piece of tissue-paper is
required. In addition to serving the purpose
stated the clamp w serves the purpose of a
door in closing the slot u , and thereby effec- 100
tually prevents dust and grit from entering
the case and getting upon the tissue-paper,
which would destroy the utility of the same
as a cleaner for eyeglasses.

In using my improved device the alcohol or other suitable cleaning agent in the receptacle D is applied to the lenses of the glasses by the soft brush G, and a piece of tissue-paper is then drawn from the casing and cut and is employed to polish the lenses.

My improved device, as will be readily observed, holds the paper and alcohol in such a manner that they may be very conveniently used for the purpose stated. It also serves to effectually exclude dust and grit from both the alcohol and paper, which is absolutely necessary when such materials are to be used for cleaning and polishing the lenses of glasses.

Having described my invention, what I claim is—

1. The herein-described device for holding and permitting of the convenient use of alcohol and tissue-paper comprising a casing having a slot in its side wall, a lip at one side of said slot having its free edge sharpened, and a spring-pressed clamp at the opposite side of the slot impinging against the lip and serving to close the slot, a rotary spool arranged in the casing and having a central opening, and a suitably-supported receptacle for alcohol arranged in the central opening of the spool, substantially as specified.

2. In a device for the purpose described, the combination of the casing comprising the

annular vertical wall having a slot and also having a lip at one side of the slot and a spring-pressed clamp at the opposite side adapted to impinge against the lip and close the slot, the bottom wall detachably connected to the annular wall and having anti-friction-rollers on its upper side and also having a central pivot-post, and a top wall connected to the upper edge of the annular wall and having a central opening, a disk mounted on the pivot-post of the bottom wall, a spool supported by said disk and having a central opening, a frame resting in the opening of the spool and having a flange at its upper end bearing on the top wall of the casing and also having an inwardly-directed flange at its lower end, a receptacle for alcohol arranged in the frame and resting on the lower flange thereof and having a stopper provided with a brush of fibrous material, and a cap-plate bearing on the top wall of the case and the upper end of the receptacle and having a central opening for the passage of the receptacle-stopper, substantially as specified.

In testimony whereof I affix my signature in presence of two witnesses.

JAMES W. BUSII.
